Company, West Allis, Wis., a corporation of
Wisconsin

Original application July 19, 1933, Serial No.
681,118. Divided and this application March
16, 1934, Serial No. 715,794

4 Claims. (Cl. 194—85)

The invention relates to coin-controlled apparatus suitable for use in vending machines and other devices.

An object of the invention is to provide a coin-controlled mechanism of durable and compact construction and of such character as to permit economical manufacture and easy assembly.

Another object of the invention is to provide a coin-controlled mechanism which is so constructed as to prevent repeated operation of the mechanism by the same coin.

The invention further consists in the several features hereinafter described and claimed.

In the accompanying drawings,

Fig. 1 is a sectional elevation of a vending machine embodying the invention, the operating parts being in retracted position;

Fig. 2 is a sectional elevation similar to Fig. 1 but showing more parts in section, the operating parts being in advanced position ready to release the coin;

Fig. 3 is a sectional view taken generally along the line 3—3 of Fig. 1;

Fig. 4 is a sectional view taken generally along the line 4—4 of Fig. 1;

Fig. 5 is a sectional view taken generally along the line 5—5 of Fig. 3;

Fig. 6 is a view similar to Fig. 1, but showing the operating parts in a partially retracted position after incomplete operation;

Fig. 7 is a top plan view of a guard member for the article-delivery passage, and

Fig. 8 is a detail sectional view of a cover for the article magazine.

In these drawings, a rectangular casing is constructed of two sheet metal parts suitably bent to shape, one of which is of inverted U-shape to form parallel side walls 15 and a top wall 16, and the other of which forms a bottom 17 having upturned side flanges 18 secured by rivets 19 to the inner faces of the side walls 15. Card holders 20 are here shown to be secured to the outer faces of the side walls 15. The opposite edge portions of the upper sheet metal parts are bent to form an inturned top flange 21 and inturned side flanges 23, and the front end of the bottom 17 has an upturned flange 25. The corner portions of the bottom 17 are preferably cut away, as seen in Fig. 4. Rubber feet 27 are fastened to the bottom 17.

The device shown in the drawings is adapted for use in restaurants, and provision is made for dispensing napkins, and also for dispensing other articles, such as sticks of chewing gum G. The dispensing of the latter articles is effected by

coin- or check-controlled mechanism hereinafter described.

An upright channel-shaped sheet metal frame 28 is mounted within the casing and has a web 29 and opposite parallel side flanges 30, which latter are spaced inwardly from the side walls 15 of the casing. The front edges of the flanges 30 lie adjacent the inner edges of the inturned casing flanges 23. The web 29 has a base flange 31 which is secured by one or more rivets 32 to the bottom 17, and the side flanges 30 have respective embossments 33 at their lower front corners secured to the inner faces of the bottom flanges 18 by a pair of the rivets 19, as best seen in Fig. 5.

An upright channel-shaped gum magazine 37 of sheet metal is mounted within the channel frame 28 and has a web 38 parallel to and spaced forwardly from the channel frame web 29. The opposite side flanges 39 of the magazine are parallel to and spaced inwardly from the side flanges 20 30 of the channel frame and are secured thereto by rivets 40 which pass through abutting embossments 41 and 42 formed respectively on the frame flanges and magazine flanges. The side flanges 39 of the magazine are provided along their front 25 edges with inturned lips 43 spaced downwardly from the upper end of the magazine to facilitate loading.

The upper end of the magazine is closed while the lower end is open and is spaced a short distance above a sheet metal platform 44. Downwardly projecting ears 40' are formed on the lower edges of the magazine side walls 39 to fit in apertures 41' formed in the platform. The platform has a down-turned front flange 45 substantially flush with the casing flanges 23. Down-turned side ears 46 on the platform are secured by rivets 47 to the side flanges 30 of the channel frame 28, and a down-turned rear flange 48 is secured to the web 29 of the channel frame by one or 40 more rivets 49.

A stack of gum sticks G in the magazine 37 is supported on the platform 44 and is surrounded by a hollow sheet metal follower 50 of rectangular cross-section loosely fitting in the magazine against relative rotation to prevent disarrangement of the gum sticks when the casing is tilted, as during the operation of loading napkins. The front face of the follower may bear a suitable advertising legend. The follower 50 may be removed from the magazine during the loading operation.

The front of the casing adjacent the gum magazine is closed by a removable sheet metal cover or front plate 51 having a suitable key- 55

operated lock 52 at its upper end with a bolt engageable behind the upper casing flange 21. The lower edge of the cover is spaced from the platform 44 to form a delivery slot 53. At its opposite lower corners, the cover is provided with rearwardly and downwardly projecting ears 54 (Fig. 8) to rest on the platform 44, the ears having downwardly projecting lugs 55 entering notches 56 formed in the platform (Fig. 4). The cover has an inspection opening 57 defined by an inturned lip 58. A gasket 59 surrounds the opening at the inner face of the cover and has a glass plate 60 bearing thereagainst and retained by flanged side tracks 61 secured to the inner face 15 of the cover, the lower ends of the track flanges being bent to form stops. The lower edge of the cover has an inturned flange 62.

A coin drawer 63 is slidably mounted in the casing below the platform 44 and has a key-operated lock 64 in its front wall with a bolt engageable 20 behind the down-turned front flange 45 of the platform. The drawer slidably rests on parallel rails 17' formed on the bottom 17.

The platform 44 slidably supports thereon an 25 ejector or feeder 65 in the form of a horizontal plate confined against upward movement by rearwardly projecting flanges 66 on the bottom of the rear wall 38 of the gum magazine. The ejector has lugs 67 at opposite ends (Fig. 4) extending 30 through horizontal slots 68 formed in the side flanges 30 of the frame 28. The front edges of the lugs 67 have notches 69 to receive the upwardly projecting arms of wire springs 70, each spring having an intermediate portion coiled 35 about a headed pin 71 secured to the side flange 30 and having a rearwardly projecting arm anchored in a notch 72 (Fig. 2) formed in the lower edge of the side flange. The bottom flanges 18 have notches 18' to provide clearance for the pins 71. 40 The springs 70 urge the ejector rearwardly against the frame wall 29, out of register with the lower end of the gum magazine. The follower 50 in the gum magazine has a beveled lower rear corner 50' so as to be lifted by the advancing ejector when 45 the magazine is empty, thus avoiding blocking of the ejector.

The upper casing wall 16 has formed therein a coin slot 73 which registers with a coin chute carried on the gum magazine and consisting of angles 50 74 spot welded or otherwise secured to the rear wall 38 of the magazine and having spaced parallel chute-forming flanges joined by spot welded connections at their rear edges to an interposed vertical strip 75. Another slot 76 is formed in 55 the upper casing wall 16 at right-angles to the coin slot 73, and receives therethrough a plunger 77 formed of a flat metal bar having a laterally bent finger rest 78 at its upper end. The plunger is slidably mounted for vertical movement in a 60 guideway formed between the front face of the frame web 29 and a channeled sheet metal strap 79 secured to this face, as by spot welding, the strap having locating lugs 80 passing through openings in the frame web.

65 The lower end of the plunger 77 has a bent hook or loop 81 which abuts against the upper surface of a coin-driving member 82 formed of sheet metal and having parallel ears 83 at opposite ends pivotally mounted on aligned pins 84 secured to embossments 85 formed on the side walls or flanges 30 of the frame 28. The embossments extend downwardly to the slots 68 and form the upper edges of these slots. The central part of the upper wall of the coin-driving member 82 70 is cut away to provide clearance for the coin chute 75

14, 75, as seen in Fig. 3, the coin chute having a converging lower end extending below the member 82. The coin-driving member is urged upwardly by a tensioned coiled spring 86 having its lower end secured thereto and having its upper end anchored to a lug 87 on the plunger guide or strap 79. The spring-urged coin-driving member lifts with it the plunger 77, the loop 81 on the plunger striking the lower edge of the strap to limit the upward movement of the plunger and 10 coin-driving member.

The ejector 65 is displaceable forwardly by a rocker frame consisting of a pair of side arms 88 joined by a coin-engaging cross plate 89. The upper ends of the arms are pivotally mounted on 15 the pins 84, and the lower ends are curved and bear in notches 90 (Fig. 4) formed in the rear edges of the lugs 67 on the ejector 65, thus preventing endwise displacement of the ejector.

A coin guide or chute is mounted on the rear 20 wall 29 of the frame 28 in alignment with the chute 74, 75 to receive the coins at the lower portion of their travel, and consists of a pair of angles 91 secured as by spot welding to the wall 29 and having spaced parallel flanges forming 25 a coin passage. A cam track or abutment 92 is secured between the parallel flanges and adjacent the wall 29 to effect the downward release of the coins after reaching a certain point in their travel. Below the lower coin guide, the ejector 30 65 and platform 44 are provided with respective openings 93 and 94 to permit released coins to drop into the coin drawer 63.

In order to prevent repeated operation of the coin ejector by a single coin or check, means are 35 provided to prevent a complete stroke of the plunger 77 unless an introduced coin is released into the coin drawer. An angle bracket 95 is secured to the rear wall 29 of the frame 28 and has a forwardly projecting flange adjacent the 40 coin chute 74, 75. A bell-crank 96 is pivotally secured to the bracket flange by a rivet 97, and has a downwardly projecting stop-forming arm which is urged forwardly by a coiled spring 98 attached to the bracket. A shorter forwardly 45 projecting arm on the bell-crank is urged downwardly by a coiled spring 99 secured at its lower end to the cross plate 89 of the ejector-displacing arms 88. The downwardly projecting bell-crank arm is movable rearwardly into the path of the 50 plunger loop 81 to prevent a complete upward stroke of the plunger unless an introduced coin is passed in the coin drawer, as hereinafter described.

A guard 100 of sheet metal has a body portion 55 below the platform 44 and provided with trunnions 101 at opposite side edges rockably supported in ears 102 projecting downwardly from the platform. At its front portion the guard has a pair of upstanding flanges 103 which pass 60 through slots 104 in the front portion of the platform to block the delivery passage 53. At its rear portion the guard 100 has a pair of upwardly bent side fingers 105 which are movable through openings 106 formed in the platform and bear 65 against the bottom surface of the ejector 65 when the latter is in its retracted position, thus holding the stop flanges 103 in their upper blocking positions to prevent withdrawal of gum sticks. The guard 100 is also urged to such position by 70 one or more leaf springs 107 secured at their front ends to the upper surface of the guard by rivets 108 and bearing at their rear ends against the bottom surface of the platform 44 rearwardly of the trunnions 101. The blocking movement 75

of the guard 100 is limited by the abutment of the front portion of the guard against the bottom surface of the platform. The guard carries upstanding cam projections 109 at opposite side edges forwardly of the trunnions 101 and movable through slots 110 formed in the platform 44. The cam projections 109 are depressed by the notched front edge of the ejector as the ejector is moved on an advancing stroke, thus rocking 10 the guard and moving the front flanges 103 thereon downwardly to unblock the delivery passage 53 for the discharge of a stick of gum. The ejector 65 has parallel slots 111 therein spaced from the front edge of the plate to permit the cam projections 109 to rise therein after the stick of gum is removed and while the plate is advanced, thus discouraging tampering.

In operation, a coin C is introduced into the coin slot 73 in the top wall 16 of the casing and drops 20 through the chute 74, 75 to the position seen in Fig. 1, where it rests on edge on the cross plate 89 of the ejector arms 88 and on the upper portion of the cam track 92 of the lower guide or chute. The plunger 77 is then depressed by the 25 finger to rock the coin-driving member 82 downwardly against the action of the spring 86. The member 82 pushes the coin downwardly and forwardly along the cam track 92, and the descending coin pushes the cross plate 89 forwardly, as 30 seen in Fig. 2, to swing the ejector arms 88 forwardly. The ejector 65 is thus advanced along the platform 44 and in the first part of its movement depresses the cam projections 109 on the guard 100 to swing the latter to unblocking position, the rear guard fingers 105 being free to rise behind the advancing ejector. The ejector in 35 its further movement pushes the lowermost stick of gum through the delivery opening 53 in position either to fall out or to readily be withdrawn 40 by the fingers. The plunger 77 is depressed further from the passing position shown in Fig. 2 to cause the coin to move over the hump of the cam track 92 and to drop into the coin drawer 63, whereupon the ejector is moved by the springs 45 70 to its retracted position, the arms 88 being also movable rearwardly with the ejector. The plunger 77 is thereupon released to the elevated position of Fig. 1. As soon as the ejector is retracted, the stack of gum sticks G drops to the 50 platform 44 in readiness for another operation.

If the plunger is released from the position of Fig. 2 in an attempt to effect repeated operation with a single coin, the coin will not drop to the coin drawer but will rise a short distance along the cam track 92 under the urge of the spring-pressed ejector. The upward movement of the plunger is limited, however, by the bell-crank 96, as seen in Fig. 6, which is urged to stopping position by the spring 99 attached to the cross plate 89 of the ejector arms 88, thereby limiting the retraction of the ejector and preventing its withdrawal from beneath the stack of gum

sticks, so as to prevent unauthorized removal of the articles. In this condition of the device the flanges 103 of the guard 100 are in their upper position, blocking the delivery passage 53. In the normal operation of the device when the coin is released into the coin drawer, the tension on the spring 99 is lessened by the complete retraction of the ejector arms 88, whereupon the spring 98 moves the bell-crank 96 out of stopping position to permit full release of the plunger to its 10 Fig. 1 position.

In assembling the device, the gum magazine 37 with its attached coin chute is fastened to the frame 28 by the rivets 40, and the frame 28 is attached to the bottom 17 by the rivet 32. The upper casing member 15, 16 is then mounted in place, a pair of the rivets 19 securing together the frame 28, the bottom flanges 18 and the side walls 15.

What we claim as new and desire to secure by 20 Letters Patent is:

1. In a dispenser, the combination of article-delivery means including a swingably mounted member having a coin abutment, a movably mounted coin-driver, a second coin abutment between which and said first-named abutment a coin is urged and passed by said coin-driver to rock said swingably mounted member on an article-delivery stroke, and means controlled by the article-delivery means to prevent repeated 25 operation of said article-delivery means by the same coin.

2. In a dispenser, the combination of article-delivery means including a swingably mounted member having a coin abutment, a swingably 30 mounted coin-driver, an actuator for swinging said coin driver, a second coin abutment between which and said first-named abutment a coin is urged and passed by said coin-driver to rock said first-named swingably mounted member on 35 an article-delivery stroke, and a movably mounted stop member shiftable to stopping position by the coin-displaced member to limit the retracting movement of the coin-driver.

3. The combination of a shiftably mounted 40 member, a movably mounted coin-driver, an abutment between which and said member a coin is urged by said driver to displace said shiftably mounted member, an actuating plunger for moving said coin-driver, and spring means 45 for retracting said coin driver and holding it in engagement with said plunger.

4. The combination of a shiftably mounted member, coin-operated means for displacing said member including a coin-driver, a stop for limiting the retraction of said coin-driver, and a resilient connection between said stop and member for moving said stop to stopping position when said member is in an advanced position.

60
